UNITED STATES PATENT OFFICE

91,616

DESIGN FOR AN INSECT SWATTER

Augustus W. Drake, Hazleton, Pa.

Application October 10, 1933, Serial No. 49,444

Term of patent 14 years

To all whom it may concern:

Be it known that I, AUGUSTUS W. DRAKE, a citizen of the United States, residing at Hazleton, in the county of Luzerne and State of Pennsylvania, have invented a new, original, and ornamental Design for Insect Swatters, of which the following is a specification, reference being had to the accompanying drawing, forming part thereof.

Fig. 1 is a face view of a swatter showing a broken handle in dotted lines, for convenience of illustration; and

Fig. 2 is an edge view of the swatter element. The dominant features of the design shown in

the drawing are the raised ribs formed on the border of the swatter element, the shape of the longitudinal reinforcements providing the handle socket formed on the swatter, the diagonal ribs on the swatter element presenting some blank spaces between them and intersecting each other at right angles to provide squares, and the square perforations in the body of the swatter element between the intersecting ribs.

I claim:

The ornamental design for an insect swatter, as shown and described.

AUGUSTUS W. DRAKE.
